UNITED STATES PATENT OFFICE.

GEORGE D. ENDY, OF PHILADELPHIA, PENNSYLVANIA, ASSIGNOR TO J. D. JOHNSON CO., OF PHILADELPHIA, PENNSYLVANIA, A CORPORATION OF NEW JERSEY.

WATER-CLOSET-SEAT-OPERATED VALVE.

1,220,831.

Specification of Letters Patent. Patented Mar. 27, 1917.

Application filed February 16, 1915. Serial No. 8,482.

To all whom it may concern:

Be it known that I, GEORGE D. ENDY, a citizen of the United States, residing in the city and county of Philadelphia, State of Pennsylvania, have invented a new and useful Water-Closet-Seat-Operated Valve, of which the following is a specification.

My invention relates to an improvement in a water closet flush tank, and consists of 10 means whereby when the seat of the bowl is occupied, the valve of said tank is primarily engaged, and then when said seat is relieved of the occupant thereof, said valve is fully 15 opened, causing thereby the refilling of the tank, causing the primary-engaging member 20 of the valve to return to its normal position.

The invention is satisfactorily illustrated in the accompanying drawing, but the important instrumentalities thereof may be varied, as long as they are included in the scope of the claims.

Figure 1 represents a vertical section of a flush tank for a water closet embodying my 25 invention including a side elevation of the bowl and appurtenances.

Fig. 2 represents a vertical section of the tank, showing certain parts in different positions from those in Fig. 1.

Fig. 3 represents a vertical section of the tank on an enlarged scale showing certain parts in different positions from those in Figs. 1 and 2.

Similar numerals of reference indicate 35 corresponding parts in the figures.

Referring to the drawings,

1 designates a flush tank, and 2 designates the discharge pipe thereof, the upper end of said pipe forming the seat 3 for the valve 4, 40 the latter having fitted freely in it the vertically arranged rod 5 which is connected by the bar 6 with the interior of the pipe 2, whereby said valve may be guided in its opening and closing motions, the stem 4^x of said valve having on its upper end the conical heads 7 which form at their places of connection the shoulder 8 which is adapted to be engaged by the nose 9 of the supplemental lever 10, which of the form of an

elbow depends on and is pivotally mounted 50 from the yoke 11, as its fulcrum, said yoke being adjustably connected by the screw 12 with the rising and lowering or sliding bar 13, said screw having thereon the nut 14 for evident purposes.

The bar 13 is guided in the boss 15 which is connected with the upper portion of the tank 1 by the angular hanger 16 which is attached to the latter by the bolt 17 or other suitable means, said bar 13 being pivotally 60 connected with one end of the swinging lever 18 whose bearing is on the ear 19, the latter being supported on the upper limb of the hanger 16.

The other end of the lever 18 is pivotally 65 connected with the ear 20, which is attached to the weight 21, the latter surmounting the raising and lowering rod 22, and serving to lower said rod, as will be hereinafter again referred to, said rod being freely inclosed 70 in the chamber 23 on the interior of the tank 1, and being extended through and below the bottom of the latter to the heel or rear end member 24 of the seat 25 of the water closet bowl 26, said seat having its axis 75 on the ear 27 rising from the bowl, its normal position being slightly raised from the top of the bowl, so that when it is occupied, it will be lowered.

The heel 24 has a vertically-extending 80 opening therein for the passage of the lower end of the rod 22 therethrough, said end being screw-threaded and having nuts 28 thereon respectively above and below said heel, so that the latter may engage with said nuts, 85 particularly the upper nut so that in the lowering motion of the seat 25, the heel 24 rises and presses upwardly against said nut and so raises the rod 22, and when the latter descends said nut bears downwardly against 90 said member and so causes the elevation of said seat, as shown in Fig. 1, said nuts 28 also serving to adjust the play of the heel 24 and consequently of the ascent and descent of the seat 25.

The portion of the rod 22 that passes through the opening in the bottom of the tank 1 is screw-threaded and has connected

55

therewith the nuts 29 which are respectively above and below said bottom so as to act as adjusting stops for said rod and connected parts.

5 Within the tank is the siphon and overflow 30 of inverted U-shape, the lower end of one limb opening into the tank 1, near the base thereof, and that of the other limb being connected with and opening into the by-pass 31, which projects from the side of the discharge tube 2 and communicates with the interior thereof below the valve seat 3 on said tube.

10 Connected with the elbow lever 10 is the arm 32 to whose outer end is attached the 15 float 33 which is submerged in the water in said tank so as to be floatable therein, and the tank is provided with a valve 34 for refilling the same.

20 The operation is as follows:—

The seat 25 is occupied whereby it is lowered and the heel 24 correspondingly raised. This lifts the rod 22 and the connected end of the lever 18, whereby the other 25 end of the latter is lowered and with it the bar 13, the yoke 11, the elbow lever 10, the arm 32 and the float 33. The nose of the elbow lever 10 rides downwardly upon the side of the upper conical head 7 of the body 30 of the valve 4 until it reaches the shoulder 8 when the float 33 causes the vertical limb of the lever 10 to turn to move said nose under said shoulder all as shown in Fig. 2, thus grappling the stem of the valve 4 and 35 causing a connection of said valve with said elbow lever, the several parts retaining their position as long as the seat 26 is occupied.

When the occupant of the seat vacates the same the rod 22 is now controlled by the 40 weight 21, when the upper nut 28 presses downwardly on the heel 24 and so raises the seat 25, and restores it to its normal position. Simultaneously therewith the lever 18 is operated whereby the sliding bar rises 45 and carries with it the elbow lever 10, and consequently the valve 4, see Fig. 3, whereby the latter is opened and the water of the tank rushes into and through the pipe 2. The siphon 30 also becomes operative to discharge the water from the lower portion of the tank into the pipe 2, the water thus being forcibly directed into the bowl 26 and so effectively flushing the same.

As the water in the tank lowers, the float 55 33 removes the nose of the elbow lever 10 from the shoulder 8 whereby the valve descends and closes on its seat. Then and as the tank refills the float rises whereby the elbow lever resumes its normal position as 60 in Fig. 1. Then the water remains in the tank until the seat is occupied again when the operations stated are repeated and the valve is opened to cause the next flushing of the bowl.

65 Should the water in the tank rise beyond

a predetermined height the escape of the excess is occasioned through the member 30 to the pipe 2, this preventing overflow of the tank.

On the elbow lever 10 at the outer terminal of the horizontal limb thereof is the shoulder 35 which is adapted to abut against the yoke 11, as in Fig. 1, to limit the motion of said lever in order to hold the latter in position, for the subsequent engagement of its nose with the shoulder 8 on the valve stem 4* when the valve ascends, it being noticed also that said shoulder moves from the yoke to permit said nose to engage with said shoulder as in Fig. 2, and furthermore, 70 as in Fig. 3, to permit the subsequent disengagement of the nose from said shoulder when the float descends, the nose then moving laterally from the shoulder, whereby the valve is permitted to drop and so close 75 on its seat 3.

Having thus described my invention what I claim as new and desire to secure by Letters Patent, is:—

1. In a flush tank water closet, a movable 90 seat for the bowl of said closet, a discharge pipe at the bottom of the tank, a valve for said pipe having its seat on said pipe, a stem for said valve, an oscillating elbow lever, a bearing piece for the latter, a slideable bar 95 member adapted to carry said bearing piece, a float connected with the horizontal limb of said elbow lever, a nose on the other limb of said lever, the upper portion of said valve stem having thereon conical heads and a shoulder with which said nose is adapted to engage, and a boss on said tank, said slideable member being freely fitted in said boss and guided by the latter, means on said lever adjacent said bearing piece engageable with 100 the latter above and below the axis of the lever on said bearing piece relatively to the different portions of said lever and means for moving said member primarily operated by said movable seat.

2. In a flush tank for a water closet, a valve on the tank, a shouldered valve stem thereon, an oscillating elbow lever having a nose on the lower end of one limb thereof adapted to engage said shoulder, a float lever connected with the other limb of said lever, a bearing piece for said lever, a slideable bar adapted to carry said means for operating said bar, and a collar on said lever adjacent to said bearing adapted to 110 abut said bearing above and below the axis of said lever on said bearing piece relatively to the different portions of said lever.

3. In a flush tank water closet, a movable seat for the bowl of the closet, a vertically 125 movable rod on said tank adapted to engage said seat, a vertically slideable bar on the tank, a swinging lever having one end pivotally connected with said bar, a weighted handle pivotally connected at one end with 130

the other end of said lever and resting upon the upper end of said rod, a discharge pipe on the tank, a valve for said pipe, connections for operating said valve intermediate of the stem of said valve and said slidable bar, a hanger, an ear on said hanger forming the axis for said lever on the tank, and a

boss connected with said hanger, said boss receiving freely said bar forming the guide therefor.

GEORGE D. ENDY.
